United States Patent Office

Des. 184,809
Patented Apr. 7, 1959

184,809

COMBINED SOFA BED AND DESK UNIT

Louis Elliott Frey, Los Angeles, Calif., assignor to Duo-Bed Corporation, Los Angeles, Calif., a corporation of Nevada

Application February 6, 1958, Serial No. 49,522

Term of patent 14 years

(Cl. D5—4)

Fig. 1.

Fig. 1 is a perspective view showing a combined sofa bed and desk unit embodying my new design, with the elements in closed position;

Fig. 2 is a perspective view of the same, with the elements in open position.

Fig. 3 is a top plan view of the same in closed position.

I claim:

The ornamental design for a combined sofa bed and desk unit, substantially as shown.
